UNITED STATES PATENT OFFICE

HOWARD H. MANNING, OF MEADVILLE, PENNSYLVANIA, ASSIGNOR TO McCROSKEY
TOOL CORPORATION, OF MEADVILLE, PENNSYLVANIA

ROTARY CUTTER

Application filed January 8, 1926. Serial No. 80,133.

This invention relates to rotary cutters and more particularly to a floating cutter block for use in connection with boring bars.

An important object of this invention is to provide novel means whereby the cutters of a cutter block or the like may be simultaneously adjusted to a greater cutting diameter by the turning of a single adjusting member, this feature providing for the accurate adjustment of the cutters with respect to the work and to each other.

A further and equally important object of the invention is to provide a simple means whereby the adjustable cutters may be securely locked in a fixed position without the necessity of removing the same from the boring bar.

Other objects and advantages will be apparent during the course of the following description:

In the accompanying drawing forming a part of this application and in which like numerals are employed to designate like parts throughout the same,

Figure 1 is a perspective of the improved floating cutter block applied;

Figure 2 is a vertical longitudinal sectional view through the same;

Figure 3 is a vertical transverse sectional view taken on line 3—3 of Figure 2;

Figure 4 is a group perspective of a pair of cutters embodied in the invention.

Figure 5 is a detail sectional view illustrating a slight modification of the invention.

In the drawing, wherein for the purpose of illustration is shown a preferred embodiment of the invention, the numeral 5 designates a flat rectangular body having a transverse opening 6 for the reception of a taper pin or other fastening device, by means of which the block may be secured in the slot in a boring bar 8.

Figure 1 illustrates that the body 5 is provided in opposite sides thereof with intersecting communicating grooves 9 arranged at an angle of approximately 120° to each other and adapted to snugly receive cutters 10 and 11, the outer ends of which are ground for cutting engagement with the work.

The inner surface of the cutter 11 is pro-

vided with a diagonal groove 12 for the reception of a tongue 14 on the opposed surfaces of the cutter 10. Figure 2 illustrates that the interfitting connection between the blades 10 and 11 extends at right angles to the axis of the block and when one of the cutters, and more particularly the cutter 11, is moved outwardly, the other cutter will also be moved outwardly a similar distance. The outward movement of the cutters is accomplished by the turning of an adjusting set screw 18 which, as clearly shown in Figure 2, is threaded into an opening 19 in the body. The forward end of the adjusting screw 18 is tapered and engages the rounded rear end of the cutter 11 at an angle with respect thereto so as to bring about the outward movement of the cutter 11 and consequently the cutter 10 when the feed screw is moved inwardly. Figure 2 illustrates that the adjusting set screw 18 is provided with a socket for the reception of one end portion of an L-shaped tool 20, by means of which the screw may be either advanced or retracted.

When the cutters have been adjusted the same are, of course, limited in their inward movement by the set screw 18 assisted by set screws 22 threaded into openings 24 in the forward end of the block 5. The inner ends 80 of the set screws 22 may be tapered for contact with the edges of the blades.

In the operation of the invention the cutters are moved inwardly to a cutting diameter smaller than that required and they are then moved outwardly through the medium of the adjusting screw 18 to the required cutting diameter whereby play which may be present between the two interlocking cutters is taken up. When adjusted the cutters are, as previously stated, firmly locked in place by the screws 22 and the device is then ready for use. The improved floating cutter block may be easily detached from the boring bar for the purpose of re-sharpening or renewing the blades or for any other purpose.

Figure 4 plainly illustrates that the cutter 10 is reduced in thickness at the portion thereof which intersects the cutter 11 so as to define the diagonal tongue 14, which

tongue is flush with the unbroken surfaces of the cutter 10.

In the form of invention illustrated in Figure 5, the bar 25 may be provided with openings or passages 26 intersecting at approximately right angles to each other and receiving blades 27, the outer terminal portions of which are sharpened as indicated at 28 for engagement with the work. In carrying out this form of invention the opposed sides of the blades or cutters 27 are formed with interfitting ribs by means of which the longitudinal movement of one cutter results in the longitudinal movement of the other cutter. This makes it possible to bring about the adjustment of the two cutters simultaneously by the turning of a single nut 30, threaded into one of the openings 26 directly behind and in engagement with one of the 20 cutters.

It is important to note that each cutter may be provided with a plurality of ribs, as shown in Figure 5, or with a single rib adapted to be received in a groove in the other cutter, it being sufficient that the connection between the cutters provides for the simultaneous adjustment of the cutters.

Having thus described the invention what is claimed is:

- 30 1. A rotary cutter comprising a body having grooves, intersecting cutters in said grooves and having the opposed sides thereof formed with cooperating motion transmitting means at an angle to the cutters, and a set screw accessible from one side of the body and engaging the rear end of one of the cutters for simultaneously adjusting both cutters.
- 40 2. A rotary cutter comprising a body having grooves, intersecting cutters in said grooves and having the opposed sides thereof formed with cooperating motion transmitting means at an angle to the cutters and imparting the endwise movement of one cutter to the other cutter, and a set screw accessible from one side of the body and engaging the rear end of one of the cutters for simultaneously adjusting said cutters, said motion transmitting means comprising an interfitting driving connection between the cutters.
- 45 3. In a boring tool, a body having oblique grooves, intersecting cutters in said grooves, one of said cutters being provided with a diagonal groove and the other cutter being provided with a motion transmitting tongue received in said diagonal groove, the tongue and groove connection between said cutters forming a means whereby the cutters are moved together, and an adjusting device engaged with the rear end of one of said cutters and adapted for simultaneously adjusting the cutters obliquely of the block through the medium of said tongue and groove connection.
- 55 4. A floating cutter block for boring bars

comprising a body having intersecting grooves, intersecting cutters in said grooves, one of the cutters being provided with a reduced portion having a motion transmitting tongue and the other cutter being provided with a groove receiving said tongue, and an adjusting device engaging one of the cutters and being constantly spaced from the other cutter, said interfitting tongue and groove connection being at an angle to the line of adjustment of the cutters.

5. A boring bar comprising a body intersecting cutters carried by the body and having cooperating motion transmitting means for coextensive adjustment of the cutters diagonally with respect to the body, and an adjusting screw carried by the body and engaged with one of the cutters, the cooperating motion transmitting means for coextensive diagonal adjustment of the cutters constituting the sole means for transmitting adjustment of said screw to the other cutter.

6. A rotary cutter comprising a body, cutters carried by the body and arranged in diagonal, intersecting relation to each other and having cooperating driving means for simultaneous and consonant adjustment of the cutters with respect to the body, and an adjusting device carried by the body and having connection with one of said cutters and being spaced from the other cutter.

7. A rotary cutting tool comprising a body, intersecting cutters carried by the body, and an adjusting device engaged with one of the cutters to move the same lengthwise and being constantly spaced from the other cutter, the opposed sides of the cutters being provided with cooperating motion transmitting means imparting the movement of one cutter to the other cutter.

8. In a rotary cutter, a body, intersecting cutters carried by the body, and an adjusting device engaged with one of the cutters and operable to move the same lengthwise and being spaced from the other cutters, said cutters being provided with mutually cooperating motion transmitting means extending at an angle to the line of adjustment of the cutters and imparting the lengthwise movement of one cutter to the other cutter.

9. In a rotary cutter, a body having slots, cutters movable endwise in said slots and having intersecting portions provided with cooperating motion transmitting means at an angle to the cutters to impart the lengthwise movement of one of the cutter to the other cutter, and an adjusting device engaged with one of the cutters to effect the simultaneous adjustment of the cutters, said adjusting device being constantly spaced from the other cutter.

10. In a rotary cutter, a body having slots, cutter movable endwise in said slots and having intersecting portions provided with mutually coacting motion transmitting means

extending at an angle to the cutters and imparting endwise movement of one of the cutters to the other cutter, and an adjusting device carried by the body and engaged with the rear portion of one of the cutters and being free from direct connection with the other cutter, said cooperating motion transmitting means being extended substantially at right angles to the axis of the body.

11. In a rotary cutter, a body having oblique grooves, cutters in the grooves and having mutually intersecting portions, means to effect movement of one of the cutters in its respective groove, and coacting means upon the said intersecting portions of the cutters for effecting simultaneous and consonant movement of the other cutter in its respective groove upon adjustment of the first mentioned cutter.

12. In testimony whereof I affix my signature.
HOWARD H. MANNING.
